PERCY HUGHES HEWITT, EDWIN A. COCKLE, AND CHARLES MATTHEWS,
OF LONDON, ENGLAND.

SEWING-MACHINE SHUTTLE.

SPECIFICATION forming part of Letters Patent No. 629,252, dated July 18, 1899.

Application filed March 29, 1898. Serial No. 675,560. (No model.)

To all whom it may concern:

Be it known that we, PERCY HUGHES HEWITT, barrister-at-law, of Oakley House, Spring Grove, Isleworth, London, W., and EDWIN ALLEN COCKLE and CHARLES MATTHEWS, boot-makers, of 34 Victor Terrace, Harrow road, Willesden, London, W., England, have invented a new and useful Sewing-Machine Shuttle, (for which an application for patent has been filed in Great Britain, dated the 7th day of March, 1898, No. 5,588,) of which the following is a full, clear, and exact description.

This invention relates to shuttle sewing-machines; and it consists, essentially, in an improved construction of shuttle, whereby it is adapted to contain an ordinary commercial bobbin or reel of thread, so as to avoid certain well-known disadvantages incidental to the use of a special spool of small capacity, such as is generally employed, these disadvantages including not only greater complication and consequent enhanced cost of the machine due to the necessity of providing special mechanism for winding the spools, but also loss of time due to the necessity of frequently stopping, removing, and accurately replacing the work and of winding thread from the ordinary reel onto the special spool, such loss bearing a high ratio to the total time worked.

The invention will be described with reference to the accompanying drawings, forming part of this specification, wherein—

Figure 1 is a longitudinal section on the plane of division between the upper and lower halves of the shuttle. Fig. 1^a is an inverted plan of the point end of the upper half of the shuttle. Fig. 2 is a longitudinal sectional elevation on line 2 2, Fig. 3, looking from the side next the shuttle-race, the internal fittings being shown in elevation. Fig. 3 is a top plan of the upper half of the shuttle. Fig. 4 is a rear end elevation of the shuttle. Fig. 5 is a cross-section on line 5 5, Fig. 3. Fig. 6 is a front end elevation of the bracket in which the spring-center for the reel is mounted.

The shuttle A, as shown in the figures, may conveniently be formed of metal stampings and is of the same general configuration as other sewing-machine shuttles, except that instead of being of D form in cross-section

and open at the flat side it is of nearly-circular cross-section, the flattened side a (which works, as usual, against the shuttle-race, so as to pass to and fro across the needle-groove) being closed and made of a width only sufficient to retain the shuttle in proper working position in the shuttle-driver or cradle.

The flattened side a of the shuttle is closed, so that no accidentally-loosened thread can escape from the shuttle, and there is no liability of the needle-point catching in the shuttle.

The shuttle is made in separable halves a' a², the joint being preferably in the horizontal central plane 1 1, Figs. 2, 4, 5, and 6, of the shuttle in order to permit of the introduction of the reel R by the removal of the upper half a'. The reel turns upon and between coned centers B C, mounted in the lower half a² of the shuttle. The back center B is fixed to or stamped up from a plate b, which is permanently attached, by rivets or otherwise to the inside of the upwardly-turned flange a³ at the heel end of the lower half of the shuttle.

The line of division between the halves of the shuttle does not pass through the plate b, which plate extends up into the upper half of the shuttle and is adapted to be engaged with the downwardly-turned flange a⁴ at the heel end of the upper half of the shuttle. For this purpose the plate b is provided with one or more rearwardly-projecting studs b', which enter corresponding holes in the flange a⁴, the union of the upper and lower halves being completed by means of a spring-latch D, contained within the point end of the shuttle. This latch is formed by a spring D, fixed within the lower half of the shuttle, as shown in Figs. 1 and 2, and is provided with a nib or nose d, which projects into the upper half of the shuttle and is adapted to snap into engagement with a catch-plate d', fixed within the upper half, so that by inserting the studs b' in their holes at the heel end of the shuttle the connection between the two parts of the shuttle may be completed by pressing the catch-plate d' into engagement with the spring D, the spring being of such form as to exert a forward pressure against the catch-plate, and thereby maintain the secure engagement

of the studs b' with the holes in the flange a^4 . The engaging surfaces of the catch-plate d' and nib d are, moreover, so beveled that the spring will tend to hold the halves of the shuttle in close connection at the point of the shuttle.

The disengagement of the halves of the shuttle may be effected by sliding the upper half a' rearward upon the lower half, (thus 10 overcoming the forward stress of the spring D until the studs b' are disengaged from their holes,) whereupon the beveling of the surfaces of the catch-plate d' and nib d will cause the spring to still further yield, so as to permit of the halves of the shuttle being completely separated by means of a direct pull away from each other. In order to insure coincidence between the meeting edges of the upper and lower halves at the point of the 15 shuttle, a steady-pin e may be fixed in the catch-plate so as to engage in a longitudinal slot e' in a plate E' , which may form part of a bracket E , hereinafter described, fixed in the lower half of the shuttle and having a 20 second slot e^2 , through which the spring D projects and by which the forward motion of the spring is so limited as to insure its maintenance when free in correct position for engagement with the catch-plate d' .

25 The forward coned center C for the reel R is carried by a sleeve c , fitted to slide upon a spindle F, fixed in the bracket E, above referred to, the sleeve being free to slide longitudinally upon the spindle, but prevented from turning upon it by a cross-pin f , fixed in the spindle and playing in a longitudinal slot f' in the sleeve, the pin-and-slot connection also serving to retain the sleeve upon the spindle when the reel is removed. The cone C is 30 formed in one with a disk C' , between which and an abutment formed by a pair of lock-nuts G, screwing upon the spindle F, is confined a spiral spring H, so as by its pressure against the disk C' to retain the reel R securely in position to rotate upon and between the cones B C as centers with sufficient friction to check the rotation of the reel so far as may be necessary to prevent more than the requisite length of thread becoming 35 unwound, the said friction also serving to impart tension to the thread. The range of elasticity of the spring H and the length of the guide-spindle F and slot f' are such as to permit of the reel being sprung into and out of 40 position in the shuttle, as well as to enable reels of various lengths, less than that of the full-sized reel shown, to be mounted between the centers B and C, while the adjustment of the stress of the spring H obtainable by means 45 of the lock-nuts G enables the initial tension to be regulated and to be maintained constant notwithstanding that reels of different 50 lengths are used.

The bracket E is permanently fixed by rivets e^3 or otherwise in the lower half a^2 of the shuttle. It comprises a boss e^4 , in which the rear end of the spindle F is permanently fixed,

and an annulus or diaphragm e^5 , the two being united by an intermediate portion, affording a convenient means of attachment to the flat side of the shuttle, as shown. The ring e^5 being adapted to fit the internal configuration of the upper and lower halves of the shuttle serves as a means of insuring coincidence of the meeting edges of the upper and lower halves of the shuttle toward the point. The internal diameter of the ring e^2 is such as to just give passage to the disk C' , which is provided with a rearwardly-extending peripheral flange C^2 , working freely through the aperture of the ring, the ring, in conjunction with the flange, serving to prevent any loose thread which may accidentally become unwound from the reel from becoming entangled with the spring G, the depth of the flange C^2 85 being sufficient to insure this result notwithstanding that the disk C' may project considerably from the ring, as would be the case where a short reel is being used.

Within the upper half a' of the shuttle is 90 mounted a thread-guide i , through which the thread runs from whatever part of the reel the thread may be drawn, this thread-guide being placed in the corner-space formed by the meeting of the flat side a of the shuttle with the adjacent tangential portion a^5 , connecting the flat and circular portions of the upper half of the shuttle. Near the top of the upper part of the shuttle is a thread-guide hole j , through which the thread passes from the 100 thread-guide i and which is partially covered by a spring-tension and guide plate k fixed by a screw k' , by means whereof the nip of the thread between the shuttle and the plate k may be varied for the purpose of 105 adjusting the tension of the thread. The plate k is provided with a stud k^2 on its under side, this stud entering a hole in the top of the shuttle and serving as a guide-stop limiting the play of the thread beneath the 110 plate k during the forward motion of the shuttle. A similar guide-stop for the thread during the rearward motion of the shuttle is formed by the forward end of the plate k being curved downwardly and upwardly, as 115 shown at l in Fig. 2, and housed in an aperture l' in the shell of the shuttle. The form thus given to the forward end of the tension-plate k , while offering no obstruction to the 120 passage of the shuttle through the needle-thread loop, admits of the thread being easily passed beneath that end of the tension-plate during the operation of threading the shuttle, as hereinafter described.

In order to prevent any possibility of the 125 shuttle-thread becoming caught under the rear end of the tension-plate k , the rear portion of said plate is curved somewhat toward the flat side of the shuttle, as shown in Fig. 3, and its extremity l^2 is bent downward so as 130 to lie snugly against the body of the shuttle, as shown in Fig. 2.

The operation of threading the shuttle, which may be very readily performed, is as

follows: The reel having been placed in position on the coned centers B C, so that the thread in unwinding will cause the reel to rotate toward the left-hand, (looking from heel to point of the shuttle,) the end of the thread is passed through the thread-guide *i* and hole *j* in the upper (and thus far detached) half of the shuttle and is then pulled around so as to pass under the forward end *l* of the tension-plate *k* and finally emerge from under said plate at the side opposite to that at which the hole *j* is situated. The thread *M* having now assumed a position (relatively to the upper half of the shuttle) substantially as indicated in Figs. 3 and 5, the upper half of the shuttle may be placed upon and locked in engagement with the lower half, as already described. The shuttle is then ready to be placed in the machine.

20 It will be obvious that the halves of the shuttle may be held together by other means than those hereinbefore described—as, for instance, by a hinge (flush with the outside of the shuttle) situated at the meeting edges in 25 the flat side *a* of the shuttle and a spring catch or catches at the opposite side.

The needle and shuttle driving mechanisms may be of any ordinary kind used for shuttle sewing-machines, the only alteration needed being such a proportioning of the dimensions as to increase the stroke of the shuttle-driver to the extent rendered necessary by the increased length of the shuttle, to increase the stroke of the needle-bar to the extent necessary to enable the shuttle to engage with and pass through the loop of the needle-thread, and to increase the range of the "take-up" sufficiently to enable it to take up the slack of the needle-thread loop after the shuttle has passed through the loop in the formation of each stitch, all these alterations being merely a matter of calculation not necessarily involving any change in the design or operation of the machine.

45 We claim—

1. A shuttle having its case divided longitudinally into two parts, said parts being provided at their heels with interlocking projections and recesses engageable by a relative 50 longitudinal movement of the parts and per-

mitting a slight hinging action, one part having a transverse pin at its point and the other a longitudinal slot receiving said pin, a spring on the point end of one part and a catch on the other engaged thereby, said spring straining the parts longitudinally to hold the interlocking parts in engagement, substantially as described.

2. A shuttle having its case divided longitudinally into two parts, said parts being provided at their heels with interlocking projections and recesses engageable by a relative longitudinal movement of parts and permitting a slight hinging action, one part having a transverse pin at its point, and the other a longitudinal slot receiving said pin, a curved spring-bar mounted on the point end of one part of the shuttle, its free end having a catch thereon and extending outward and toward the point, and the other part of the shuttle 70 having a catch engageable by the spring, the engaging surfaces being sloping to strain the parts into interlocked position, substantially as described.

3. A shuttle having spool-receiving centers, 75 one of which is slidable longitudinally and has a central axial hole, a pin supported at one end and entering said hole, the pin and center having one a longitudinal slot, and the other a pin entering said slot and limiting its 80 movement, a spring bearing against said movable center and an adjustable support for said spring, substantially as described.

4. A shuttle having spool-receiving centers, 85 one of which is slidable longitudinally and has a central axial hole, a pin supported at one end and entering said hole and having a threaded section, the pin and center having one a longitudinal slot and the other a pin entering said slot and limiting its movement, a 90 spring bearing against said movable center and locking-nuts threaded upon the pin and forming an adjustable support for the spring, substantially as described.
